UNITED STATES PATENT OFFICE.

EDSON E. SHEPARD, OF WATERTOWN, ASSIGNOR OF ONE HALF TO TORRENCE ROWLEE, OF MORRISTOWN, NEW YORK.

SASH-HOLDER.

SPECIFICATION forming part of Letters Patent No. 286,559, dated October 9, 1883.

Application filed July 22, 1882 (Model.)

To all whom it may concern:

Be it known that I, EDSON E. SHEPARD, a citizen of the United States of America, residing at Watertown, in the county of Jefferson and State of New York, have invented 5 certain new and useful Improvements in Sash-Fasteners; and I do hereby declare the following to be a full, clear, and exact description of the invention, such as will enable others skilled 10 in the art to which it appertains to make and use the same, reference being had to the accompanying drawings, and to letters or figures of reference marked thereon, which form a part of this specification.

15 This invention relates to certain new and useful improvements in sash-fasteners; and it consists in the novel construction and combination of the parts, as will be hereinafter set forth, and pointed out in the claim.

20 This invention is designed more especially as an improvement upon the invention shown and described in Letters Patent No. 201,956, which were granted to me April 2, 1878.

25 In the annexed drawings, which are representations of my invention, Figure 1 is a perspective view, showing my invention as applied to a window-sash. Figs. 2 and 3 are perspective views, showing the parts detached and separated; and Fig. 4 is a detached plan 30 view of one of the parts.

35 In the annexed drawings, A represents a casting, which is provided with a flat bearing-surface, a, and a stirrup, b, which has parallel sides and is curved opposite the plate a. The U-shaped stirrup of the casting A is provided 40 on its upper surface, at the center of its curved portion, with an upturned lug, c, and on its under side with parallel guides d d, as shown in Fig. 2.

45 The hand piece or lever B consists of a single casting, which is provided on its under side with a circular bearing-plate, e, and eccentric or cam C, of a sufficient size to extend over the stirrup b. Above this cam is formed a handle or lever, D. The circular bearing-plate e of the casting B is of the same diameter as the space between the parallel sides of

the stirrup b. This plate is perforated in its center for the reception of a screw, f, by means of which screw the parts of the sash-fastener are held together and attached to the window-frame.

50 Before attaching my sash-fastener to a window-frame two longitudinal and parallel grooves are cut in the frame, near its edge, of a sufficient depth to receive the lugs d d of the casting A. These grooves, in conjunction with the casting B, insure a straight movement of the casting A to and from the window-jamb.

55 The hereinbefore-described sash-fastener is secured to the window-frame by a single screw, the head of which fits into a recess formed in the casting B, as shown in Fig. 3, and the flange of the eccentric-cam, bearing upon the surface of the stirrup b, holds the casting A 60 securely in place.

65 In operating this sash-fastener the handle D is turned upon the stationary pivot or screw, and the eccentric bears either upon the plate a or lug c, causing the casting A to slide either 70 to or from the window-jamb, thus tightening or loosening the window-sash in the frame.

75 I am aware that sash fasteners or holders have heretofore been constructed having a lever with a cam formed thereon and a sliding bolt arranged within a frame; and I do not claim such, broadly, as my invention, the object of my invention being to provide a sash-holder of few parts, which can be sold cheaply 80 and which will operate effectively.

85 What I claim as new, and desire to secure by Letters Patent, is—

In combination with a sash-frame having transverse parallel grooves, the casting A, with bearing-plate a, stirrup b, having flanges d d 85 and lug c, and means for operating and attaching the same to the sash-frame, substantially as shown and described.

In testimony whereof I affix my signature in presence of two witnesses.

EDSON E. SHEPARD.
